UNITED STATES PATENT OFFICE.

WILLIAM H. PRIESS, OF BOSTON, MASSACHUSETTS, ASSIGNOR TO WIRELESS SPECIALTY APPARATUS COMPANY, OF BOSTON, MASSACHUSETTS, A CORPORATION OF NEW YORK.

ELECTRICAL CONDENSER.

Application filed October 22, 1919, Serial No. 332,421. Renewed September 26, 1925.

This invention relates to improvements in electrical condensers of the plate or sheet type, especially of the type wherein the condenser is divided into sections and the sections connected in series for high potential service, altho not limited to series condensers, and the invention consists of certain improvements in the means for clamping the stack.

If the dielectric such as mica and conductors are not in intimate contact, that is to say if a second dielectric in addition to the mica is present between the conductors serious losses which may even extend to break down occur.

15 My invention is especially applicable to the type of stack in which the two ends are at difference of potential and is embodied preferably as an insulating clamp, that is, a clamp in which the two ends of the stack are connected by or insulated from each other by a member comprising insulating material. This material, must, however, be rigid and possess very little give and stretchability, and for this purpose certain forms of vitreous insulating material such as porcelain, quartz glass and lavite have been found very serviceable. An advantage of my form of clamp resides in the fact that the capacity of the condenser remains constant with time and 30 use.

My clamp may comprise means exerting a live pressure upon the opposite ends of the stack and maintaining the elements of the stack under constant pressure irrespective of 35 variations in length thereof due to temperature changes, an increment of increase or decrease in the length of the stack being allowed by a corresponding change in the clamp due to its inherent resiliency or elasticity thus maintaining a constant pressure upon the ends of the stack. When the stack expands the clamp yields enough to allow this and returns to its original position upon the contraction thereof. My clamp is therefore elastic, that is, when a strain is placed upon it and then removed the clamp returns to its original position or state.

An object of this invention is to provide a clamp which will maintain the insulators or 50 dielectrics and conductors as above mentioned in intimate contact.

Another object of the invention is to provide a construction of clamp which will insulate the opposite ends of the stack from each 55 other, maintain a substantially constant pres-

sure on the ends of the stack irrespective of expansion or contraction thereof due to temperature changes and hold the mica or other insulators and conductors in intimate contact.

60 This invention consists further in details of construction and combination of parts hereinafter more particularly described and claimed.

In the accompanying drawings which form 65 a part of this specification Fig. 1 is an end elevation illustrating for the purpose of this application what I now consider to be the preferred form of the invention.

Fig. 2 is a side elevation, with parts in 70 section, of the structure of Fig. 1 in a casing.

Fig. 3 is a perspective view of a modified form of the invention, the casing (of Fig. 2) being omitted.

Fig. 4 is an end elevation of the type of 75 condenser illustrated in Fig. 3.

Fig. 5 is an end elevation of another form of the invention, the casing (of Fig. 2) being omitted.

Fig. 6 is an end elevation illustrating still 80 another embodiment of the invention, the casing being omitted.

Fig. 7 is an end elevation of still another form of the invention, the casing (of Fig. 2) being omitted.

Fig. 8 is a plan view of a further form of 85 the invention.

Referring to Figs. 1 and 2 the space X, Fig. 2, shown around the stack K and its clamp A in the wax or insulating filler protector or casing B is intended to illustrate the wax casing or coating around the stack for the purpose of preventing brush discharges and excluding moisture and air, and also preferably but not necessarily around 90 the clamp. This is preferably a mass of wax cast in protector B as a permanent or temporary mold and filling the space X and surrounding stack K and permissively clamp A and it may be no more than a thin or surface coat providing that it excludes moisture and air from the interior of the stack and assists in preventing brush discharges.

100 In the type of condenser on which this invention is an improvement, the condenser consists of a stack K of plates or sheets, this stack being adapted for high potential service by being divided into sections which are electrically connected together in series by various means in accordance with the estab- 105 110

lished practice for several years, and in which any desired manner of connecting these sections in series may be adopted, but for purposes of illustration I apply the arrangement 5 as shown in Figs. 1 and 2.

The sheets as usual consist of successively located conductors and insulators. In the present condenser such insulating and conducting sheets may be of any desired material but I use metal foil (as lead) for the conducting sheets and mica for the insulating sheets and my condenser is therefore known to the trade as a mica condenser, or specifically a high potential mica condenser or as a transmitting condenser for use in radio communication. A desirable feature of a construction of this kind is the small volume of the entire apparatus, but the high potential developed across the ends of the sheet-stack 20 makes this a difficult problem. The same is true in respect to exposing a minimum of the conducting parts which are at high potential. Other problems have arisen in connection with the importance of the construction 25 whereby the condenser stack is most desirably held under compression and kept permanently dry and free from air inside of the stack and whereby brush discharges are prevented.

I have illustrated clamp A Figs. 1 and 2, applied to a series of sections S constituting the stack K, the opposite ends of each section having foil bunches constituting terminals 1. Connectors 2 of sheet copper are interposed 30 between the sections, one end of each connector 2 being electrically connected to the foil bunch 1 at one end of one section and the opposite end of the connector being electrically connected to the foil bunch 1 at the 35 opposite end of the adjacent section thus connecting the sections in series. Separators 3, usually mica are placed between each connector and the adjacent section upon both sides of the connector for the purpose of insulating the adjacent portions of adjacent 40 sections from each other and from the connectors.

The specific stack construction above described is more fully described, illustrated 45 and claimed in the patent to Byron Macpherson, No. 1,446,650 of February 27, 1923, and is illustrated here merely to show an application of the present invention, it being understood that the clamp embodying the present invention is applicable to other types of stack.

In assembling the apparatus, the stack K Figs. 1 and 2 is mounted upon or engages at 50 one end an elastic base plate or clamping member 4 composed preferably of tempered spring steel and before assembly assuming a bow or convex form as illustrated in broken lines Fig. 1.

The opposite end of the stack is provided 55 with a cast steel pressure member 5 covering

the end and having at opposite sides outwardly and upwardly projecting lugs 6.

Clamp A comprises blocks or plates 7 and 8 of rigid insulating material, preferably quartz, lavite or the like, vitreous material, 70 and these insulating plates are provided at their upper portions with openings 9 (Fig. 1) made to correspond to the inclination of and to fit the inclined lugs 6 and in openings 9 are fitted or socketed the lugs 6 of the cast steel pressure member 5, thus supporting the insulating plates 7 and 8 at opposite sides of the stack over the surfaces of which these parts of clamp A extend, Fig. 2. The lower portions of the insulating blocks or plates 7 75 and 8 are each provided with a series of transversely extending metal inserts 10 thru which and thru the lower end of the block are screw holes 11.

Threaded in these holes and thru the 80 base plate 4 are adjusting screws 12 securing top pressure member 5 insulating blocks or plates 7 and 8 and the base plate 4. All together in clamping relation 85 around the stack K. In the particular embodiment of the invention here illustrated there are three adjusting screws upon each side of the stack, and disposed at intervals Fig. 2, across insulating sides 7. 90 8 of clamp A. Insulating plates 7, 8 of clamp A are of substantial width and height (Fig. 2), forming an insulating barrier and operating with wax X between them and stack K in insulating the latter. The screws of each insulating block or plate 7 and 8 are 95 in alinement and the two sets are arranged parallel to each other. The base plate 4 is provided with suitable openings 13 which taper upwardly to receive heads 14 of the screws 12 and to allow their adjustment. 100

The inserts 10 provide means for securing a solid grip for the screws 12 and to distribute the stress uniformly over insulating blocks or plates 7 and 8. 105

Upon the adjustment of the screws 12 the 110 spring steel base plate 4 is straightened out or flexed drawing the same and the pressure plate 5 toward each other clamping the elements of the stack in intimate contact at the required pressure. Securing the insulating 115 blocks or plates 7 and 8 to the member 5 as illustrated insures that the former will be maintained locked and secured to the member 5 for the reason that as the screws 12 are adjusted to tighten the clamp the upper ends 120 of the insulating plates 7 and 8 tend to move inwardly toward the inner ends of the lugs 6 by reason of the inclination thereof.

The insulating plates 7 and 8 furthermore, by reason of this connection are spaced from 125 the sides of the stack and the ends adjacent to the base plate 4 diverge from said sides. The wax X may fill this space between stack K and insulating sides 7-8.

The adjusting screws 12 are located at the 130

opposite sides of the stack and upon adjustment apply pressure to the ends of the stack equally at opposite sides whereby the pressure of clamp A is transmitted evenly or 5 uniformly over the ends of the stack without danger of tilting or dislocating the elements of the stack and compressing them more on one portion than another. Vitreous insulating plates 7, 8 are the tension members of 10 clamp A. Upon the adjustment of the screws 12 base plate 4 is flexed to assume the position or form shown in solid lines Figs. 1 and 2 transmitting a constant live pressure to the ends of the stack by reason of its tendency to assume a convex form.

The insulating tension blocks or plates 7, 8 are rigid or nonstretchable and capable of 20 withstanding a heavy load so that the clamp by reason of its elastic member is highly elastic always maintaining a constant pressure and never works loose.

When the stack K is placed in casing B and secured as hereinafter described, base plate 4 flexes or moves at opposite sides, upon 25 variations in the length of the stack, around the points of connection, the ears 15, of the plate 4 to the casing as an axis.

The clamping plate 4 may be of any strong metal such as tempered spring steel or may 30 be of combination of metals sweated together such as steel and brass and so arranged as to automatically yield or flex as the temperature varies maintaining a constant pressure great enough to keep the elements of the 35 stack in intimate contact.

In assembling the apparatus, the stack K is preheated and the screws 12 are tightened with the stack under pressure. All this will be done before placing the unit in the casing 40 and securing it thereto thus allowing inspection of the stack before being surrounded by the wax or other insulating filler.

Of course, the stack K of this condenser like any condenser stack of sheets requires 45 initial treatment during manufacture for the purpose of removing internal air and moisture and consolidating the stack of sheets before being covered with the coating of wax X which thereafter is to keep out the air and moisture. Any of the various well known methods may be used for this treatment, which usually includes immersion in molten wax, in or out of vacuum, and a compression or variation of the compression of 50 the stack. For the latter purpose a clamp is used during the process but in this instance the clamp A, that is, the stack K and its clamp A may act as a unit during the treatment. The stack and clamp in the present 55 case are assumed to have been properly treated as above and in proper condition of clamping pressure and are ready to be inserted in casing B and surrounded by wax X or other filler.

The wax protector B is so called because 65 it may serve initially as a mold for the wax casing X when the latter fills container B yet thereafter B may remain as a permanent part of the assembly for the purpose of protecting the wax filler which it does whether 70 the filler be merely a coating around the stack or a thick mass filling protector B, or filling the space (Fig. 1) between stack K and the insulating plates 7, 8.

In preparation for the casting of the wax 75 in receptacle B the stack K and the clamp A in place around it are inserted in protector B as a mold and protector. If desired indeed the receptacle B may be used previously for the above treatment of the stack i. e., all 80 three parts, stack K, clamp A and receptacle B may be used together in the preliminary treatment of the stack.

The wax is then cast in the mold B around 85 the stack and clamp. For this purpose the base plate 4 is provided with ears 15 having openings 16 adapted to fit around lugs 17 projecting upwardly from the bottom of casing B. Screws 18 are threaded into screw holes 19 in the central portion of lugs 17 securing the plate 4 to the casing B. These 90 points of attachment of the base plate 4 to the casing B are arranged at opposite sides of the former and upon a line extending between and parallel to lines on which the adjusting screws 12 lie. As mentioned above this construction allows the portions of the base plate 4 to which the screws 12 are attached to flex or move around these points of connection as an axis when the length of the 95 stack varies.

Before the casing B is filled with the wax X or other insulating filler one end of the lowest section S of stack K is connected by a lead 20 to the casing B, being soldered to the base plate 4 and preferably secured by one of the screws 18, as shown in Fig. 2 at the right. The casing B if of metal may constitute the low potential terminal L P T, Fig. 2. Threaded to top compression member 5 of clamp A at right angles thereto is a brass terminal stud threaded at its upper end and constituting the high potential terminal H P T of the condenser. It will thus be seen that in the construction herein disclosed the end members 4 and 5 constitute in fact the terminals of the stack, altho not necessarily. A lead 21 extends from one end of the uppermost section of the stack and is electrically connected to the cast steel pressure member 5 by being clamped thereunder. The casing B has a cover C of insulating material. This cover is provided with a vertically extending opening 22 to receive the stud H P T and with an upper recess 23 to receive a knurled metal insert 24 threaded to the upper portion of the stud. A lock nut 25 is threaded upon the upper end of the terminal stud above in-

sert 24 and above this is provided a nut 26 whereby any suitable electrical connection may be clamped.

The expressions "high potential terminal" 5 and "low potential terminal" are, of course, only relative terms as the actual high potential and low potential depend entirely upon the condition of the circuit in which the condenser is used.

10 At the time when the stack and clamp are cast in wax X the high potential stud H P T is left projecting above the wax in preparation for the application of the condenser cover. After the wax in casing B has been 15 cooled and solidified the top or cover C is applied on gasket G interposed for water tightness and around the terminal stud H P T. The insert 24 and the nuts 25 and 26 are then applied to the stud outside the cover and the 20 cover is secured to the casing by the screws C'.

The particular condenser here shown has a capacity of 0.004 micro-farad in extensive use for transmitters in radio communication. In the example disclosed each section S of 25 stack K may consist of the size, number and thickness of sheets which will give it a capacity as above mentioned.

The wax protector or casing B may be of any desired material or shape because it has 30 no necessary mechanical or electrical cooperation with the condenser stack and the specific embodiment of clamp A herein disclosed. Thus it may consist of any simple wood or fiber box of any size, or shape if desired. In fact as the stack K and clamp A (see Fig. 1), constitute a complete operative condenser they may be used without any covering over the casting or coating of wax, but, of course, it is extremely advantageous 35 to provide a wax protector and to also have it of metal as the most practical form of protector during use of the condenser.

I prefer that the casing B be of metal such as aluminum moulded thin to shape as a 40 single and economic construction. Aluminum is light, relatively cheap and easily moulded but any other material may be used such as a tin or sheet brass casing.

The walls of container B are substantially 45 vertical and the clamp A herein described is compact and allows the use of a casing B of relatively small size. The insulating plates 7 and 8 are of a substantial width, as great as or greater than the width of the sides of 50 the stack and of a length substantially as long as the stack whereby the adjacent portions of the sides of the stack are insulated, in addition to the wax, if such wax be used, from the adjacent walls of the casing preventing brushing.

In the construction herein disclosed the clamping means is entirely distinct from the insulating cover C and independent thereof, the latter playing no part in compressing 55 the stack. The cover therefore, if used, may

consist of any suitable insulating material of low structural strength such as electrose, or the like, molded to shape.

Referring to Figs. 3 and 4 I have illustrated a clamp embodying another form of 70 the present invention.

The end sections S³ of stack K³ disclosed in Figs. 3 and 4 are provided with suitable leads 30 and 31 adapted to be connected to the high potential terminal and the low potential terminal as above described if a casing be used; otherwise they may be connected to any suitable terminals.

Upon one end of the stack, Figs. 3 and 4, is placed a metal pressure plate 32 of an area 80 corresponding to the area of the end of the stack. Interposed between the pressure plate 32 and the adjacent end of the stack, which is built up of mica and foil as described above, is an insulating pad 33 to prevent injury to the end of the stack. At the opposite ends of the stack is an insulating sheet 34 for the same purpose.

My clamp A³ in the present instance comprises plates or blocks 35 and 36 of rigid insulating material such as above described, or even fairly strong non-vitreous material such as the stronger forms of bakelite-dilecto, and of a length substantially the length of the stack and of a width substantially the width 95 of the stack forming an insulating barrier and arranged upon opposite sides of the stack. The outside of each insulating block or plate is provided with a pair of transverse grooves 37 arranged adjacent the ends thereof and inclined inwardly toward their adjacent ends. These grooves 37 receive elastic or resilient claw shaped metallic clamping members 38 and 39 extending around the ends of the stack and having arms 40 extending 100 toward one another along the sides of the stack and terminating in fingers 41 projecting into and engaging the grooves 37 in insulating plates 35, 36.

These claw shaped clamping members 38, 110 39 are of spring steel and constitute a pair of elastic clamping members forming a clamp of the double spring type as distinguished from the clamp disclosed in Figs. 1 and 2 in which only one of the end members is elastic. 115 The results achieved however, are substantially the same, that is, when the clamp including insulating tension members 35, 36 is adjusted to a given pressure maintaining the elements of the stack in intimate contact, the 120 clamp maintains a constant live pressure upon the ends of the stack irrespective of variations in length in the stack due to temperature changes.

In order to adjust initially the pressure 125 exerted by this clamp upon the ends of the stack one of the members 38 and 39, as here shown, member 38 engaging end pressure plate 32 is provided with adjusting means for drawing up the other member tightly against 130

its end of the stack and for pressing plate 32 tightly against its end of the stack, compressing the elements of the stack. For this purpose this means comprises a plurality of set 5 screws 42 extending thru member 38 and having their inner ends engaging the pressure plate 32 as an abutment. These screws are 10 symmetrically arranged whereby the pressure upon adjustment can be distributed uniformly over the ends of the stack to insure perfect contact of the elements thereof. It will be seen that as the screws 42 are adjusted the pressure plate 32 and the clamping member 39 will be moved toward each other clamping 15 the ends of the stack. The clamping members 38 and 39 are elastic or resilient and become flexed by this adjustment maintaining a constant live pressure upon the ends of the stack whereby the elements of the stack are 20 maintained in intimate contact as above described. Upon the adjustment of the screws 42 the pressure is transmitted to the opposite end of the stack thru the insulating plates or blocks 35 and 36 as tension members and the 25 fingers 41 are drawn up in the grooves 37 with the parts, (members 38 and 39 and plates 35 and 36) tightly connected.

Referring to the modification of Fig. 5 stack K⁵ of series-connected sections S⁵ rests 30 upon or engages at one end a spring plate or pressure member 51 of tempered spring steel, having a natural tendency to assume a convex form as illustrated in broken lines in the drawing, this construction being the same as 35 or the equivalent of the plate 4 described in connection with Figs. 1 and 2. At the opposite end of the stack is a metal pressure member 52 having a convex upper surface 52^a and also having an area substantially as great as 40 the end of the stack. The compression members 51 and 52 may constitute the electrical terminals of the stack which are generally at different potentials, if so desired. In this form a U shaped yoke 53 of rigid insulating 45 material, preferably vitreous as above described, has an intermediate portion 54 extending over or engaging the convex surface 52^a of the top pressure plate 52 and has ends 55 extending toward the base plate 51, diverging 50 slightly from the sides of the stack. Adjusting screws 56 connect the ends of the yoke 53 to the base plate 51. The screws pass thru the base plate 51 and are threaded into the 55 ends of the yoke 53 and thru metal inserts 57 therein. These inserts insure that the screws receive a firm grip and distributes the stress 60 uniformly over the insulating material. It will thus be seen that as the screws 56 are adjusted the end compression members 51 and 52 will be drawn toward each other putting insulation 53 under tension and clamping the stack sections S⁵ and the elements thereof into intimate contact and the bottom curved pressure plate 51 will straighten out, exerting 65 a live resilient pressure upon the ends of the

stack maintaining the pressure constant irrespective of variations in the length thereof due to temperature changes.

The construction of Fig. 5 is similar to the construction of Figs. 1 and 2 but with insulating connectors 7 and 8 replaced by a single insulating yoke 53.

Fig. 6 illustrates another form of the invention in which the insulating tension members are employed and in which spring pressure is applied to the ends of the stack by compressing a coil spring.

In this construction the stack K⁶ of series-connected sections S⁶ rests upon or engages at one end a plate or pressure member 61 which 80 covers the end of the stack and may be of any suitable rigid material preferably metal. The opposite end of the stack is provided with a metal pressure member 62 covering the end of the stack. The compression members 61 and 62 may constitute the electrical terminals of the stack and for this purpose the member 62 is provided with a brass terminal stud 63 at right angles thereto and adapted to extend thru the cover of the casing, if such casing 90 and cover be used as described in connection with Figs. 1 and 2.

The members 61 and 62 are maintained clamped against the ends of the stack by the following means. Plates or blocks 64 of 95 rigid insulating material, preferably vitreous as above described, are arranged at right angles to member 61 and secured thereto by screws 65 extending thru member 61 into the blocks 64 at opposite sides of the stack and thru metal inserts 66 therein for the purpose above described. The opposite ends of the blocks 64 are connected by a metal cross piece 67 by means of screws 68 at opposite sides of the stack and extending thru the cross piece 100 into the adjacent ends of blocks 64 and thru metal inserts 69 therein for the purpose specified. The insulating plates or blocks 64 are arranged parallel with opposite sides of the stack in spaced relation thereto and project 110 beyond the end on which the member 62 is placed whereby the metal cross piece 67 is spaced from said metal member 62. The plates 64 act as insulating barriers insulating 115 the sides of the stack as above described.

A coil spring 70 encircles the terminal stud 63 (which extends thru a hole 71 thru cross pieces 67), and is interposed between the member 62 and cross piece 67 which constitute abutments for the spring. Upon the adjustment of either screws 65 or 68, or both, the bottom compression member 61 and top cross piece 67 are moved toward each other, putting insulation 64 under tension and compressing the spring 70, increasing the pressure on top pressure member 62, the spring pressure being transmitted to the opposite end of the stack and member 61 thru the tension plates 64 whereby the members 61 and 62 maintain a spring pressure on the ends 130

of the stack. This spring 70 is of sufficient strength to maintain the sections S^6 and the elements thereof in intimate contact and to exert a constant live pressure upon the ends 5 of the stack irrespective of variations in the length of the stack due to temperature changes.

In the construction of Fig. 6 the opposite ends of the stack are preferably at high potential differences and the construction provides a clamp which properly insulates the two ends of the stack from each other and at the same time provides a spring pressure which achieves the desired result. It will 10 therefore be seen that the invention is applicable to a clamp in which parts are rigid vitreous insulating material and in which the spring pressure is secured by a separate spring as distinguished from the clamp hereinbefore described in which an end compression member itself is springy.

In Fig. 7 I have illustrated a form of the invention in which the spring pressure is applied to the ends of the stack K^7 having series 25 sections S^7 by a coil spring under tension as distinguished from the construction shown in Fig. 6 in which the coil spring is under compression.

The stack is provided at one end with a 30 pressure member 71 covering the end of the stack and at the opposite end with a pressure member 72 covering that end of the stack. These members may comprise any suitable rigid material preferably metal if 35 used as terminals and need not be resilient. Mounted outside of or upon the member 72 parallel thereto is a member or cross piece 73 to which are attached (at right angles thereto upon opposite sides of the stack) 40 plates or blocks 74 of rigid insulating material, which extend along the sides of the stack toward the member 71, the member 72 being provided with suitable openings 75 to guide the blocks 74. The blocks 74 may be 45 secured to the member 73 in any suitable manner as by threading or may be integral therewith if 73 be of insulating material. Coil springs 76 at opposite sides of the stack are connected at 77 to the free ends of the 50 insulating blocks 74 and at their opposite ends to the pressure member 71, the insulating plates 74 terminating short of the member 71. The member 73 is provided with a plurality of set screws 79 extending there- 55 thru and engaging pressure member 72 which acts as an abutment for the set screws. These screws are symmetrically arranged so that the pressure can be adjusted uniformly on the ends of the stack maintaining perfect 60 contact of the elements.

When the screws 79 are adjusted the springs 76 and insulation 74 are tensioned and the pressure members 71 and 72 are pressed or drawn against the ends of the 65 stack. The springs 76 being under tension

exert a live pressure upon the ends of the stack and hold the elements thereof in intimate contact under constant pressure irrespective of variations in the length of the stack due to temperature changes.

In this construction also the end members 71 and 72 may constitute the electrical terminals of the stack, the opposite ends of which are preferably at high potential differences and insulated from each other by 75 the insulating plates 74.

In Fig. 8 I have illustrated a form showing another of the numerous ways in which the present invention is capable of embodiment. In this instance the stack K^9 comprises sections S^9 built up as above described and connected in series in any suitable manner, although for purpose of illustration they are shown connected in the same manner as in Figs. 1 and 2. At the opposite ends of the 80 stack, which are generally at a difference of potential, may be located square plates 100 of rigid insulating material which are at least substantially the same area as the foil sheets constituting the elements of the stack 85 for the purpose of receiving the pressure of the clamp A^9 transmitted to the ends of the stack.

In this construction the clamp A^9 comprised two elastic pressure end plates or 90 members 101 of tempered spring steel engaging the blocks 100 and connected together by plates 102 of rigid vitreous insulating material as above described and arranged upon opposite sides of the stack and forming 100 an insulating barrier at the sides of the stack and spaced therefrom. The metal end plates 101 overlap the edges of the insulating blocks or plates 102 and are adjustably screwed or connected thereto by screws 103 passing thru the metal plates 101 and into the adjacent edges of the insulating plates 102 and thru the transversely extending metal inserts 104 placed in the metal plates 102 to insure a better grip for the screws 103 and to distribute 110 the stress uniformly over the insulation 102. In the form here illustrated there may be six screws passing thru each metal plate 101, three at each side of the stack whereby the 115 pressure can be evenly and uniformly adjusted over the ends of the stack by way of insulation 102 under tension.

The above construction provides an elastic durable clamp in which a live pressure is maintained upon the ends of the stack by 120 elastic members at both ends, which are flexed and placed under tension when the clamp is adjusted to the required pressure by means of screws 103. The plates 101 tend naturally to assume a convex form as shown in broken lines Fig. 8 (left) and when adjusted by screws 103 are straightened out which results in an inherent tendency for these plates to exert a live pressure against the ends of the stack, maintaining a constant live pressure 125 130

on the ends of the stack and the elements thereof in intimate contact irrespective of variations in length of the stack due to temperature changes. The above described stack and clamp constitute a complete condenser per se.

In the several forms of the invention described above, the insulating member or members constituting part of the clamp are placed under tension when the clamp is adjusted to the required pressure.

The clamp and stack disclosed in Figs. 1 and 3-8 constitute a complete condenser, yet the unit may be used with a separate casing and treated as hereinbefore described, if so desired.

The metal parts 10 of the stack clamping means of Figs. 1-2 and 5-8, and the metal part 38 of Figs. 3-4, constitute an important feature of the invention in respect of the vitreous tension-insulation and the threaded clamp-securing and adjusting means. Taking Fig. 1 as typical, and irrespective of any clamp-flexibility as in bottom compression element 4, said member 4 and the adjusting screws 12 are of metal in accord with correct engineering design, the compression screws being located at a compressing angle with metal end compression member 4. But the insulating material of barrier 7-8, ideal when of vitreous material as an insulator having sufficient strength to withstand the tension strains on the clamping means, is not adapted structurally to withstand all strains when in direct combination with pressure screws 12. Hence, both ends of the screws are caused to engage with metal members, i. e., 4 and 10, the latter not only receiving the threads of screws 12, but being of a shape and relative arrangement which provide an ample bearing surface for engagement with insulating material 7-8, i. e., as sufficient a bearing surface as that between the other compression member 5 and the other end of insulating barrier 7-8, this bearing function of metal members 10 being in addition to their function in holding the threads of metal screws 12. Thus metal bearing members 10 and metal screws 12 may assume various shapes and locations relative to tension insulation 7-8 and the stack S, in respect of the function of bearing members 10 in receiving the screws 12 and in affording sufficient bearing surface with tension insulation 7-8. When metal screws 12 are screwed up, the metal bearing means 10, in which they engage, are forced in a direction away from the remote end of stack S, thereby tending to force insulation 7-8 in the same direction; the actual effect being that while all the parts, including the remote end of stack S, are held substantially rigid, save screws 12 and compression plate 4, yet said screws and plate are moved toward the remote end of stack S, thereby putting it under compression. In

Figs. 3-4, the metal bearing means 10 of Fig. 1 and Figs. 5-8 is replaced by the metal bearing member 38, which bears against insulation 35-36 in the specific way above described in respect to Figs. 3-4.

In brief, I have developed a clamp, of which several forms are illustrated and described, for keeping the series-sectional, high-potential condenser stack at all times under a constant pressure, said clamp comprising means for insulating the ends of the stack from one another, these ends having a high potential difference across them, and the insulating portion of the clamping means constituting a tension element, altho consisting of vitreous material, such material being not only well adapted for high potential insulation, but also having adequate structural strength to withstand the high tension strains to which it is subjected in the construction and service of the condenser.

In all of the examples shown either the upper or the lower stack-compression member or both may be used as end terminals of the condenser unit.

It is to be understood that the invention is not limited to the embodiments and features specifically shown and described herein, but such embodiments and features are subject to change and modifications without any departure from the spirit of the invention.

I claim:

1. In an electrical condenser, a stack having its ends at a difference of potential and a clamp comprising pressure members upon the ends of the stack and rigid means consisting of structural insulating material and having portions extending along the sides of the stack and constituting the connection between said pressure members and transmitting the clamping stress longitudinally through said insulating means.

2. An electrical condenser comprising a stack, pressure members engaging the ends of the stack and rigid insulating means adjustably connecting said members and tensioned by adjustment.

3. In an electrical condenser, a stack having its ends at a difference of potential, and a clamp comprising pressure members engaging the opposite ends of the stack and rigid means consisting of structural insulating material and having portions extending along the sides of the stack and constituting the connection between said pressure members; and mechanism permitting tightening said pressure members against the stack ends thereby putting said insulating connection under tension.

4. An electrical condenser comprising a stack, a pressure member at one end of the stack and having upwardly and outwardly projecting lugs, a pressure plate at the opposite end of the stack; members of insulating material each having openings at one end and

receiving said lugs thereby connecting said insulating members to said pressure member; and means for connecting the opposite ends of said insulating members to said pressure plate.

5. In an electrical condenser, a stack composed of sheets of conductors and dielectric and having its opposite ends at a difference of potential, pressure plates upon opposite ends of the stack, one at least of said plates being springy, and rigid insulating tension means connecting said plates, whereby a spring pressure is exerted over the ends of the stack to hold said sheets together.

10. 6. In an electrical condenser, a stack of conductors and dielectrics and a clamp for said stack including a spring plate arranged transversely of an end of the stack and in parallelism with the conductors and dielectrics for exerting spring pressure over the ends of the stack.

15. 7. In an electrical condenser, a stack composed of sheets of conductors and dielectric and having its opposite ends at a difference of potential, and a spring clamp therefor comprising means insulating the opposite ends of the stack from each other and means for adjusting said clamp for exerting a spring pressure on the stack.

20. 8. An electrical condenser comprising a stack and a clamp therefor including an elastic plate at one end of the stack, means for securing said plate at an intermediate portion thereof to a suitable support and means for connecting said plate upon opposite sides of said securing means to the opposite end of the stack.

25. 9. In an electrical condenser, a stack of sections connected in series and comprising sheets of foil and dielectric, the opposite ends of said stack being at a difference of potential and clamping means exerting uniform pressure over opposite ends of the stack, and including means insulating the opposite ends of the stack from each other and a spring plate arranged to have its surface facing an end of the stack and held under stress whereby said pressure is maintained resiliently.

30. 10. In an electrical condenser of the sheet type, the combination with a stack of dielectric and conducting sheets arranged in serially-connected sections to have a high potential difference across its ends, a clamp for holding the stack under high compression, said clamp comprising a metal clamping member arranged adjacent to and to act against an end of the stack, metal means including a movable compressing member at the other end of the stack, and means consisting of rigid structural insulating material constituting the operating mechanical connection between said metal clamping member and metal means, said insulating means taking the tensile stress of the clamp and insulating the two metal end structures from one another.

11. An electrical condenser, comprising dielectric and conducting sheets arranged in serially-connected sections whereby the opposite ends of the stack in service have a difference of potential, and clamping means arranged to exert uniform pressure over said stack ends, said clamping means including means insulating said stack ends from one another and including also a spring plate under stress whereby said pressure is maintained resiliently.

16. 12. The combination with a series-sectional sheet condenser stack having a high potential difference across its ends, of two metal end compression means respectively located at the two end faces of said stack; and tension means of rigid structural insulating material extending along the sides of the stack, having its ends mechanically connected with said metal end compression means, and insulating them from one another; the mechanical connection between said rigid structural tension means and at least one of said metal end compression means including metal threaded pressure-applying means located at a compressing angle with said compression means, and including also bearing means of metal engaged by said metal threaded means and itself having a mechanical connection with the adjacent end of the rigid structural tension means; all whereby the screwing up of the metal threaded means causes the metal bearing means to put the rigid structural tension means under tension and force the two metal end compression means against the stack-ends.

21. 13. The combination with a series-sectional sheet condenser stack having a high potential difference across its ends, of stack-clamping means comprising metal compression means respectively located at the faces of the two ends of the stack; said clamping means comprising also rigid vitreous tension means extending along the sides of the stack, having its ends mechanically connected with said two compression means and insulating them from one another; the mechanical connection between said vitreous tension means and at least one of said compression means including metal threaded pressure-applying means located at a compressing angle with said compression means, said mechanical connection including also bearing means of metal engaged by said metal threaded means and itself having a mechanical connection with the adjacent end of the vitreous tension means.

26. 14. In an electrical condenser of the type including a stack having a high potential difference across its ends, the combination with such stack, of clamping means comprising two metal compression means respectively located at the end faces of the stack, said clamping means comprising also rigid vitreous tension means mechanically con-

nected with said metal compression means, and extending along the sides of the stack and constituting an insulating barrier for the stack from end to end thereof.

5 15. Stack-clamping means for series-sectional sheet-stack condensers, which comprises two metal compression means respectively having surfaces for engagement with the faces of the respective ends of the stack, 10 and tension means consisting of rigid vitreous insulating material mechanically connected with said two compression means.

15 16. Stack-clamping means for series-sectional sheet-stack condensers, which comprises metal end compression members connected together by tension means consisting of vitreous insulating material.

20 17. In a high potential condenser, the combination with a series-sectional condenser stack having a high potential difference across its end faces, of means for subjecting the stack to high mechanical compression across its ends, said means including metal devices engaging the ends of the stack and 25 therefore themselves at high potential difference, said means including also tension means constituting the operating mechanical connection between said metal end devices, said tension means consisting of structural 30 insulating material withstanding the high tensile stresses and serving to insulate said metal end devices of the clamping means from one another.

18. An electrical condenser and a clamping system therefor comprising the following elements, namely the condenser comprising dielectric and conducting sheets arranged mechanically in a stack and arranged electrically in serially connected sections thereby causing the two opposite end faces of the stack in service to possess a high potential difference; and the clamping system mechanically exerting a substantially constant live pressure upon the opposite ends of the stack while insulating them from one another by 45 virtue of its construction comprising compression means extending over the surfaces of the end faces of the stack and compressing together the sheets of the stack, tension means extending along the sides of the stack and electrically insulated from the edges of the conducting stack-sheets, means permitting adjustment of the cooperating compression and tension means to produce the desired compression on the stack ends; said clamping system including at least one elastic metal portion which it at the same potential as one end of the stack and which by its elasticity permits increases and subsequent decreases of the length of the stack while permitting 50 the clamping system to maintain substantially constant stack-compression; and means electrically insulating said elastic metal portion from the other end of the stack at high potential difference.

WILLIAM H. PRIESS.
